UNITED STATES PATENT OFFICE

THOMAS OWEN MORAN, OF IPSWICH, QUEENSLAND, AUSTRALIA.

GARMENT-SUPPORTER.

No. 828,951.

Specification of Letters Patent.

Patented Aug. 21, 1906.

Application filed August 29, 1905. Serial No. 276,297.

To all whom it may concern:

Be it known that I, THOMAS OWEN MORAN, a subject of the King of Great Britain and Ireland, and a resident of Ellensborough 5 street, Ipswich, in the State of Queensland, Commonwealth of Australia, have invented a certain new and useful Invention entitled Garment-Supporters, of which the following is a specification.

10 The objects of the invention are to produce an article for holding up stockings or socks without stopping the circulation as when garters are used and to overcome the downward drag when suspenders are used, also to provide a trouser-clip for cyclists which can be 15 removed from the sock and used for the trousers.

It consists in a short length of elastic web to the ends of which are fastened metal plates 20 formed with hooks in front and having side lugs or projections and front end projections which fold over and clip the elastic web.

Referring to the drawings which form part of this specification, Figure 1 is a top view; 25 Fig. 2, a side view; Fig. 3, a view of under side.

A is a length of elastic web, B and B' stamped metal plates, having lugs or projections b, b', b², b³, b⁴, b⁵, b⁶, and b⁷ and end projecting pieces c and c', all formed integrally 30 with the plates, which fold over upon the webbing and are pressed down, securely fastening the plates to the webbing.

D is a thumb-piece formed integrally with the plate and bent upward, as shown in Fig. 35 2. The piece c' is punched out of this piece D, leaving a hole c² therein.

The extended ends of the plates are formed into hooks e, e', e², and e³.

In using the invention one end of the holder 40 is hooked into the article, the elastic web stretched by the thumb-piece with thumb and finger, and the other end hooked in, which takes up the slack of the stocking or 45 sock and tightens the same upon the leg without interfering with the circulation.

Having now described my invention, what I claim as new, and desire to secure by Letters Patent, is—

A garment-supporter consisting of a length 50 of elastic material, and a metal plate connected to each end thereof, each plate being of rectangular form and having lugs on both side edges and a projecting piece at one end thereof adapted to engage the elastic material and projecting portions, bent into hook 55 form, at one end edge on each side of the projecting piece and a thumb-piece on one plate.

In witness whereof I have hereunto set my hand in presence of two witnesses.

THOMAS OWEN MORAN.
